METHOD OF AND APPARATUS FOR VALVING
BAGSHarry E. Lee and Frank M. Holter, Oswego, N. Y.,
assignors to St. Regis Paper Company, New
York, N. Y., a corporation of New York

Application September 7, 1939, Serial No. 293,792

13 Claims.

(Cl. 93—8)

This invention relates to the valving of bags, and more particularly to applying adhesive between selected portions of the walls of the bag and valve during the valving operation.

More particularly the invention relates to a method of applying adhesive during the folding of the valve and to apparatus for carrying out this method.

In valve bags, such as disclosed in Bates et al. Patent No. 1,752,292, April 1, 1930, for "Paper bag," a multi-ply paper bag has one corner turned in to form a valve, after which the end of the bag is closed, except for the valve opening, by a sewn seam. The bag is filled through a tube thrust through the valve. After the filling is complete, the tube is withdrawn, and the pressure of material within the bag closes the valve.

The paper of the valve is quite heavy in large bags containing heavy loads, such as cement bags, and unless the valve folds properly, openings are left through which the contents of the bag may sift. It has been found that adhesion of the valve to the walls of the bag at chosen points facilitates the proper folding of the valve, and it is the purpose of this invention to apply such adhesive advantageously.

In the accompanying drawings forming a part of this specification:

Figure 1 is a perspective view of valving apparatus embodying the invention;

Figs. 2 to 7, inclusive, are partial perspective views of the valving apparatus showing successive positions during the valving operation;

Fig. 8 is a somewhat diagrammatic plan view of the paste-applying apparatus of the valver, and

Fig. 9 is an elevation of the paste-applying apparatus.

The apparatus comprises a stationary frame providing a table 10 on which there is mounted a shaft 11 for oscillation about a pivot 12. The shaft is driven by a suitable belt 13 and carries a roller 14 which is adapted to contact the upper surface of a bag 15 and feed it to the right, as viewed in Fig. 1, when the shaft is lowered. When the bag reaches the position in which it is shown in Fig. 1, it contacts the lower end of a switch lever 16 and operates a suitable mercury switch within switch box 17. This closes circuits to actuate a solenoid, not shown, for lifting shaft 11 and for initiating the movement of the valving apparatus proper.

The apparatus for actually tucking in the valve comprises clamps 18, butterfly spreading members 19, a tucking finger 20, a pressing mem-

ber 21 and abutment plates 22. These are driven by suitable connections forming no part of the present invention and which need not be described in detail. As indicated above, the rotation of shaft 23 is initiated by the movement of lever 16.

The operation of the switch in a box 17 also initiates the operation of pasting apparatus which is best shown in Figs. 8 and 9. This apparatus comprises a slide 25 which is reciprocable in a guideway 26 and is moved by an arm 27' which may be actuated by any suitable connections to the driving apparatus.

The slide 25 carries a holder 27 (see Figs. 2, 3 and 4) for glue pads 28.

In the position in which the apparatus is shown in Figs. 1 and 9, the holder 27 and slide 25 are withdrawn from the end of the bag so that the glue pads are in contact with a glue roller 29 which is rotated and supplied with glue from a pump 30 in ways which will be obvious without detailed disclosure. The pump and glue roller are operated by means of a motor 31 indicated in Fig. 9.

Mounted upon a rockshaft 32 there are pressure pads 33 which are normally held by a spring 34 in the position in which they are shown in Fig. 1.

The gluing apparatus thus far described, including the guideway 26, is mounted in a frame which is slidable in a guideway 35 substantially at right angles to guideway 26. The frame is adjusted in guideway 35 so that it will be in line for proper cooperation with the valve devices.

A frame 40 is pivoted upon brackets suitably supported on the table 10 (see Fig. 1). An arm 41 extends from frame 40 and is operated by a slide 42 which in turn is connected to a cam, not shown, which is driven in timed relation to the valving apparatus. The frame 40 carries a plurality of rollers 43 which are constantly driven by a belt 44 from any suitable source of power. When the frame 40 is lowered, the rollers 43 press upon the upper surface of a bag which has been valved and discharge it from valving position.

While the operation of the apparatus has been indicated in connection with the foregoing description, it will be briefly reviewed for convenience in understanding the purpose of the invention and the specific way in which it is carried out in the illustrated example.

Multi-ply paper tubes each of proper length to form a bag, are formed in any suitable manner. One of these lengths, collapsed and with a gusset

fold along the side at the end of which a valve is to be formed, is fed in any suitable manner onto the table and slid towards the valving apparatus until its corner is caught beneath roller 14, which continues the forward movement of the tube until its end moves switch lever 16. The movement of lever 16 effects the lifting of roller 14, and the starting of the valving and pasting apparatus.

By operation of the valving device, the gusset of the tube is held collapsed at a distance from the end of the bag by clamps 18 while butterfly spreading members are oscillated to spread the gusset closely adjacent to the clamps. The apparatus is then in the position in which it is shown in Fig. 2.

During the spreading of the butterfly members, holder 27 with pads 28 has been moved from its position with the pads in contact with glue roll 29 towards the valve corner of the bag. Continued movement inserts the pads between the folded in corner 50 of the bag and the spread apart bag walls, as indicated in Fig. 3. Substantially simultaneously with the completion of this movement, rod 32 is oscillated, bringing members 33 against the outside of the turned in corner and pressing the inside of the turned in corner against pads 28 so as to insure the transfer of adhesive from the pads to the inner side of the turned in corner. The members 33 are then swung back and pads 28 withdrawn, as indicated in Fig. 4. In this connection, it should be noted that the movement of carrier 27 and pads 28 is in a line substantially parallel with the position of the turned in corner, resulting from the action of the butterfly members, the position which the corner occupies during the application of the adhesive.

In the position indicated in Fig. 4, it will be clear from comparison with other figures that the finger 20 contacts the center of the turned in corner and immediately thereafter, as indicated in Fig. 5, member 21 is oscillated to press the sides of the inturned corner against the spread apart sides of the bag, as held by members 22. After this operation, the members 20, 21 and 22 are released and the butterflies returned to their original position, the initial turning of the butterfly spreaders being preferably prior to the withdrawal of members 20 and 21. Members 22 may follow the spread apart walls of the bag as members 20 and 21 are withdrawn and insure the return of the spread apart walls to their original position, if desired.

At the close of the operations just described, a suitable connection from the valving apparatus, not shown, results in the lowering of arm 41 and frame 40 so that rollers 43 contact the upper surface of the bag. At the same time, the lowering of frame 40 effects, through means not shown, an opening of the circuit controlled by switches in box 17 so that the operation of the valving apparatus cannot be initiated again while the frame 40 is lowered. When the valved bag length has been fully discharged sidewise from the valving position, frame 40 is raised and the circuit is reclosed so that the movement of lever 16 can then initiate a repetition of the movements just described. The frame carrying roller 14 is also lowered in operative position to feed forward another bag length upon the conclusion of the valving operations, and the lateral movement of the valve bag length.

It will be seen that a method has been devised in accordance with which adhesive is applied be-

tween the bent in valve corner and the spread apart walls of the bag during the valving operation. After the valving has been completed, it would be difficult to introduce this adhesive properly and would require a separate operation to do so. Any attempt to introduce the adhesive prior to the valving operation would result in smearing the adhesive to undesired locations during the valving operation. By applying the adhesive at the moment when the walls are spread apart and the valve corner is bent in, and before the spread apart walls are collapsed upon the bent in corner, it is possible to apply the adhesive without requiring a separate operation and to have it positioned where desired without smearing it upon surfaces where it is not desired. The accurate application of the adhesive is sustained by pressing the bent in corner against the pads so as to insure the transfer of the adhesive to the inner surface of the valve corner and the prompt pressure of the walls together against the adhesive insures its proper action in uniting the surfaces where desired. It will be seen that this method of operation is very simple, but advantageous.

While one form of apparatus has been disclosed, it is clear that the adhesive might be inserted by other means or even by hand during the valving operation, and while features of the apparatus are important in their own right, no particular apparatus is necessary for carrying out the broad idea of the method.

What we claim is:

1. In valving bags, the method which consists of spreading apart the walls of a bag tube at its open end adjacent the corner where a valve is to be formed, and bending the wall at said corner towards the median line of the bag, inserting adhesive between the spread apart walls and the bent over corner, and thereafter bringing the spread apart walls together in their original position with the bent in corner therebetween.

2. In valving bags, the method which consists of spreading apart the walls of a bag tube at its open end adjacent the corner where a valve is to be formed, and bending the wall at said corner towards the median line of the bag, inserting adhesive between the spread apart walls and the bent over corner, thereafter bringing the spread apart walls together in their original position with the bent in corner therebetween, and pressing the walls against the bent in corner where the adhesive is located between them.

3. In valving a gusseted bag, the method which consists in spreading apart the gusset and side walls of the tube adjacent the corner where the valve is to be formed, bending in the straightened end of the gusset at the corner of the bag, inserting adhesive between the bent in corner and the spread apart side walls of the bag, and bringing the spread apart walls together in their original position with the bent in corner therebetween.

4. In valving a gusseted bag, the method which consists in spreading apart the gusset and side walls of the tube adjacent the corner where the valve is to be formed, bending in the straightened end of the gusset at the corner of the bag, inserting adhesive between the bent in corner and the spread apart side walls of the bag, bringing the spread apart walls together in their original position with the bent in corner therebetween, and pressing the side walls against the bent in corner where the adhesive is located between them.

5. Apparatus for valving bags comprising means to spread apart the side walls of a bag adjacent one corner thereof, means to bend the corner between the spread apart side walls and towards the median line of the bag, means to insert adhesive between the bent in corner and the spread apart sides, and means for bringing the spread apart walls together in their original position with the bent in corner therebetween.

6. Apparatus for valving bags comprising means to spread apart the side walls of a bag adjacent one corner thereof, means to bend the corner between the spread apart side walls and towards the median line of the bag, means to insert adhesive between the bent in corner and the spread apart sides, means for bringing the spread apart walls together in their original position with the bent in corner therebetween, and means for pressing the walls of the bag against the bent in corner where the adhesive is located therebetween.

7. Apparatus for valving a gusseted bag comprising means to spread the gusset of the bag apart, adjacent one corner and thereby spread the side walls of the bag, means to bend the gusseted corner between the spread apart side walls and towards the median line of the bag, means to insert adhesive between the bent in corner and the spread apart sides, and means to bring together the spread apart walls in their original position with the bent in corner therebetween.

8. Apparatus for valving a gusseted bag comprising means to spread the gusset of the bag apart adjacent one corner and thereby spread the side walls of the bag, means to bend the gusseted corner between the spread apart side walls and towards the median line of the bag, means to insert adhesive between the bent in corner and the spread apart sides, means to bring together the spread apart walls in their original position with the bent in corner therebetween, and means for pressing the walls of the bag against the bent in corner where adhesive is located therebetween.

9. Apparatus for valving bags comprising means to spread apart the side walls of a bag adjacent one corner thereof, means to bend the corner between the spread apart side walls and towards the median line of the bag, means to insert adhesive between the bent in corner and the spread apart sides, and means for returning the spread apart walls to their original position with the bent in gusseted corner therebetween.

* 10. Apparatus for valving bags comprising means to spread part the side walls of a bag

5 adjacent one corner thereof, means to bend the corner between the spread apart side walls and towards the median line of the bag at an angle to the side of the bag and slanting towards the open end of the bag, and adhesive-applying means comprising paste pads and means to move the paste pads in rectilinear lines substantially parallel to the position of the bent in corner and insert the paste pads between the bent in corner and the side walls of the bag.

10 11. Apparatus for valving bags comprising means to spread apart the side walls of a bag adjacent one corner thereof, means to bend the corner between the spread apart side walls and towards the median line of the bag, means to insert adhesive between the bent in corner and the spread apart sides, and means for bringing the spread apart walls together over the bent in corner, the adhesive-applying means comprising pads and means to move the pads in a line substantially parallel with the bent in corner at the time the adhesive is applied, and means for pressing the bent in corner against the pads.

15 12. Apparatus for valving bags comprising means to spread apart the side walls of a bag adjacent one corner thereof, means to bend the corner between the spread apart side walls and towards the median line of the bag, means to insert adhesive between the bent in corner and the spread apart sides, means for bringing the spread apart walls together over the bent in corner, the adhesive-applying means comprising pads, means to move the pads in a line substantially parallel to the bent in corner at the time the adhesive is applied, means to apply paste to the pads when they are removed away from the corner, and means to press the bent in corner against the pads when the pads are inserted between the corner and the spread apart walls.

20 13. Apparatus for valving bags comprising means to spread apart the side walls of a bag adjacent one corner thereof, means to bend the corner between the spread apart side walls and towards the median line of the bag, means to insert adhesive between the bent in corner and the spread apart sides, means for bringing the spread apart walls together over the bent in corner, said apparatus comprising a switch controlling the initiation of the movement of the valving mechanism and the adhesive-applying mechanism, means for removing the bag length after the valving operation, and means controlled by the means for removing the bag length for resetting said switch.

25 HARRY E. LEE.
FRANK M. HOLTER.
